ATTORNEY.

UNITED STATES PATENT OFFICE.

GEORGE L. KRAATZ, OF MARTINS FERRY, OHIO, ASSIGNOR TO HASKINS GLASS COMPANY, A CORPORATION OF WEST VIRGINIA.

SHADE OR REFLECTOR.

981,576.

Specification of Letters Patent. Patented Jan. 10, 1911.

Application filed February 12, 1910. Serial No. 543,623.

To all whom it may concern:

Be it known that I, GEORGE L. KRAATZ, a citizen of the United States of America, and resident of Martins Ferry, county of Belmont, and State of Ohio, have invented certain new and useful Improvements in Shades or Reflectors, of which the following is a specification.

This invention relates to improvements in glass shades or reflectors for artificial lights, and it has for its object to provide a shade or reflector of the prismatic type having means whereby rays of light emanating from an inclosed lamp or burner are diffused or disseminated in such manner as to soften and render the reflected rays less strong and penetrating.

A further object is to provide a glass shade or reflector wherein the reflecting prisms have outer plain facets, giving said prisms a truncated form adapted for permitting the passage of light rays in radial directions. And a still further object is to provide a reflector having outer facets on the reflecting prisms, adapting it for transmitting, as well as for reflecting, light, and having on said facets bead-like projections each of which is adapted for concentrating light rays at a point outside the reflector, said projections consequently giving to the reflector a highly ornamental appearance.

In describing the invention in detail, reference is had to the accompanying drawing, forming a part of this specification, in which—

Figure 1 is a side elevation of a shade or reflector embodying my invention; Fig. 2 is a vertical section on the line 2—2, Fig. 1; and Fig. 3 is a horizontal section on the line 3—3, Fig. 2.

Referring to said drawing, in which like designating characters distinguish like parts throughout the several views—1 indicates the body of the glass shade or reflector, which may be of any preferred form and which is furrowed on its exterior with V-shaped substantially parallel grooves 2, forming prisms

3 of truncated shape between adjacent grooves, each prism terminating in a longitudinal facet 4, parallel to its base, instead of in the usual edge.

Formed on the facets 4 and spaced apart in any preferred manner are bead-like projections 5, each of which constitutes an extremely small plano-convex lens of a bull's-eye type adapted for concentrating light rays. As is obvious, the facets 4 permit the transmission of light rays which would otherwise, were complete prisms employed, be reflected; and the employment of a large number of the bead-like, or lens-like, projections 5, while ornamenting the shade or reflector, serves to concentrate some of the light rays and to so direct them that a soft, diffused and, at the same time, strong light will be directed radially.

Having thus described my invention, what I claim as new, and desire to secure by Letters Patent, is—

1. A glass reflector having its exterior surface furrowed with substantially parallel V-shaped grooves which are separated so as to leave longitudinal plain surfaces therebetween, and bead-like projections formed on said plain surfaces.

2. A glass reflector having its exterior surface furrowed with substantially parallel V-shaped grooves, prism-like ribs occupying the spaces between adjacent grooves, said ribs terminating in outer longitudinal facets, and bead-like projections formed on said facets.

3. A glass reflector of the prismatic type wherein the prisms terminate in plain narrow facets which lie parallel to their bases, and plano-convex lens-like projections formed on said facets.

In testimony whereof I affix my signature in presence of two subscribing witnesses.

GEORGE L. KRAATZ.
